ROLL POLISHING APPARATUS

William W. Leach, Warren, Ohio, assignor to
The Aetna-Standard Engineering Company,
Youngstown, Ohio, a corporation of Ohio

Application August 11, 1933, Serial No. 684,695

6 Claims. (Cl. 51—253)

The object of my invention herein described is to provide a device by which the upper roll of a mill, such as a two-high sheet mill, may be polished continuously, or intermittently, during the operation of the mill. The device is intended to be used in conjunction with a polisher for the lower roll, such as is shown in Patent No. 1,977,001 issued to me, and is to be driven therefrom. As explained in my said application, the polishing of the lower or driven roll is more important than the polishing of the upper roll, but it is often desired that both rolls should be polished to secure maximum results in rolling.

In the accompanying drawings:

Fig. 1 is an end view of a two high mill, with a lower roll polisher, equipped with the top roll polisher described herein, same being in position to polish the upper part of the front face of the roll; Fig. 2 is a top view of the mill shown in Fig. 1; Fig. 3 is an elevational view of the mill shown in Fig. 1 from the rear, showing the relation between the two polishers, the mill proper being shown in phantom; Fig. 4 is an end view of such a mill equipped with the top roll polisher described herein, same being in position to polish the lower part of the rear face of the roll; Fig. 5 is a top view of Fig. 4; Fig. 6 is a detail drawing showing sectionally a longitudinal cross section of the screw shaft and housing with elements mounted thereon; Fig. 7 is an end view of a polishing stone holder with its mountings and a dirt collector; Fig. 8 is a side view of a support in bracket and mounting; Fig. 9 is a top view of Fig. 8; Fig. 10 is a cross sectional longitudinal view of a portion of the housing and screw shaft showing the nut mounted on the said screw shaft.

My device may be mounted to polish the upper part of the front face of the upper roll, or may be used to polish the lower part of said roll on the opposite side of the mill. When used in the position first stated, the device is removably mounted on the inside faces of the windows in the mill housing as shown in Figs. 1 and 2. For this purpose angle irons 1 are mounted on said faces forming ledges upon which the polishing device rests. For purposes of adjustment, as when using a larger roll, liners are placed on said ledge raising the polisher to the desired position. The device is further held in operative position by the pull of the tension means hereinafter described.

The polisher comprises a tubular screw housing 2 through which a screw bearing shaft 3 is rotatably mounted on bronze bushings which are held in place in said housing by set screws. Mounted on the screw part of said shaft and

within said tubular housing is a nut 5 which carries a boss 6 projecting through a slot 7 in said housing, which slot is of sufficient length to permit said nut to travel back and forth the entire length of the face of the roll to be polished. The screw housing rests in the angles formed by the mill housing with the angle irons mounted thereon, and carries on either end thereof a circular ball bearing 8 of a well known type through which the ends of the screw bearing shaft pass 10 and in which said screw shaft revolves.

Mounted on said boss 6 is a stone holder bracket 9 which carries on its free end a polishing stone holder 10, so positioned that a polishing element 11 mounted therein will bear against the face of the roll to be polished. Fixedly mounted on said tubular housing at either end of said slot 7 are two collars 12 carrying projecting levers 13. Mounted on, and connecting, said two levers is a bar 14 having a Z cross section to give it rigidity.

In the back of the stone holder 10 are mounted two rollers 15 which bear closely against one face of said Z bar. The nut 5, boss 6, bracket 9, and stone holder 10 are in an assembly in fixed relation. A fixed relation also exists between the screw housing 2, the collars 12, levers 13 and the Z bar 14 in another assembly. The nut 5 is mounted on the screw portion 16, of the screw shaft 3, and is moved therealong as the screw shaft is revolved. This movement is the only possible movement between the two assemblies, as the stone holder is so positioned that it travels along one face of the Z bar against which it is pressed as the polishing stone carried thereon is pressed against the face of the roll.

For the purpose of applying pressure to force the polishing element against the roll to be polished, two collars 17 carrying fixed levers 18 are non-rotatably mounted, one at either end of the screw housing 2 and beyond the mill housings. To these levers spiral springs 19 are attached, which springs are put under tension by means of chains 20 which may be adjustably secured in forked anchors 21, mounted on the outside of the mill housings. Tension on said springs causes the two assemblies above described to tend to move about the screw shaft as an axis and the polishing element carried on stone holder 10 is pressed firmly against the face of the roll to be polished.

The screw shaft 3 is preferably made hollow so that a stream of water for cooling may be forced therethrough. For this purpose suitable couplings are provided at either end thereof.

Power to rotate the screw shaft 3 and the screw

16 cut thereon and force the nut 5 carrying the stone holder 10 forward and back across the face of the roll is provided through a sprocket wheel 22 and a sprocket chain 23, driven by the lower 5 roll polisher. This sprocket wheel 22 is provided with the number of teeth needed to give the desired speed of rotation, and is revolvably mounted on one end of the screw shaft outside the mill housings. Between said sprocket wheel and 10 the mill housing a half coupling 24 is mounted by two set screws. Mounted between said half coupling and said sprocket wheel, and engaging a flat face on each, is a fibre disk 25. On the other side of said sprocket wheel and engaging 15 the opposite face is a second fibre disk 26. Loosely mounted on said screw shaft beyond said second disk and in close contact therewith is a thrust plate 27, in which are three spaced holes 28 for engaging thrust pins hereinafter described. 20 Fixedly mounted by set screws on said screw shaft, beyond the thrust plate is a thrust collar 29. Fixedly mounted in the inside face of said thrust collar are three thrust pins 30 which engage the three holes 28. Said collar also carries 25 three holes 31 therethrough in which are mounted coil compression springs 32. In the outer ends of said holes 31 are threaded set screws 33 which bear against said springs and compress them against the thrust plate 27.

30 Loosely suspended from a pin 34 mounted in the stone holder bracket 9 is a hook shaped bracket 35 which envelopes the polishing stone and holder and catches the dust and chips which result from the polishing operation. Dust or 35 chips which may adhere to the face of the roll are scraped therefrom by a knife edge 36 mounted on the lower lip 37 of said bracket and held against the roll by the weight of the bracket.

When it is desired to polish the upper roll on 40 the lower portion of its rearward face as shown in Figs. 4 and 5, the assembly and drive are similar, but the polisher is mounted on brackets 46 which are attached to the faces of the mill housings. Such a bracket is shown assembled in Figs. 45 8 and 9. A plate 38, fixedly attached to the side of the mill housing, carries studs 39 and 40. Loosely mounted on stud 39 is hook member 41 which has a slot 42 near the end opposite the hook end of the member, and rotatably mounted on a 50 stud 47 in the side of said hook member 41 is wedge member 43. The slot 42 engages stud 40, and wedge member 43 in operative position, is forced down between said hook member 41 and a head carried on said stud 40. A handle pin 44 55 is mounted in said wedge member, and a handle 45 is provided on hook member 41 beyond the slot 42. To remove the polisher from the mill, wedge member 43 is lifted releasing the hook member 41. The handle 45 of said hook member may then be lifted which drops the hook end upon which the polisher assembly rests, and the latter may then be withdrawn from the mill.

In operation the sprocket chain from the lower roll drives the sprocket wheel mounted on 60 the end of the screw shaft. The compressive elements of the friction clutch are so adjusted that the screw shaft is rotated in its housing. The boss carried by the nut mounted on said shaft fits in the slot in the housing and prevents rotation 65 of the nut. Rotation of the screw shaft causes the nut to move along the length thereof carrying with it the stone holder bracket and the stone holder. When the driving means for the lower polisher reverses, to carry the lower roll polisher 70 back across the face of the lower roll, the move-

ment of the sprocket chain driving the upper roll polisher will also reverse. Should the nut and polisher mounted thereon in the upper roll polisher reach one end of the slot before the lower roll polisher reverses, the action of the 5 slip clutch will permit movement of the sprocket chain to continue in the same direction until movement of the lower roll polisher is completed and movement reversed, even though the nut, having arrived at the end of the slot in the upper 10 roll polisher, renders same inoperative until movement is reversed. By this means inequalities of movement between the polishers on the lower and on the upper roll are automatically adjusted, and the upper roll is fully polished synchronous with the full polishing of the lower roll.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In combination in a machine for polishing the upper roll of a mill, a screw shaft mounted parallel to said roll, a nut mounted on said screw shaft which nut controls the movement of mountings for holding a polishing element, means transmitting reversing rotation from a lower roll polisher to said screw shaft, whereby the said nut is caused to move forward and back a controlled distance along said screw shaft, and a slip clutch between said means and said screw 35 shaft, whereby said means may continue to operate when said nut reaches the limit of said controlled distance before the rotation of said lower polisher reverses.

2. In an automatic polisher for the roll of a 40 mill, in combination, a hollow supporting member having a longitudinal slot therein, a worm screw mounted through said member, a worm screw nut mounted on said worm screw, a polishing element carrier mounted on said nut through the said slot, means whereby reversing rotation is imparted to said worm screw, and a slip clutch between said means and said worm screw whereby said means may continue to operate until ready to reverse after the said nut and carrier thereon 45 mounted has reached the limit of movement in either direction as determined by the length of said slot.

3. In an automatic polisher for the roll of a 55 mill, in combination, a hollow supporting member having a longitudinal slot therein, mounted through said member a worm screw with a longitudinal hole therethrough for the passage of a cooling medium, a worm screw nut mounted on said worm screw, a carrier, adapted to hold a 60 polishing stone, mounted on said nut by means of an element engaging said slot, means whereby said worm screw is reversibly rotated, and a slip clutch between said means and said worm screw.

4. In an automatic polisher for the roll of a mill, a hollow supporting member having a slot longitudinal thereof, a worm screw shaft mounted therethrough, a worm screw nut mounted on said worm screw, a carrier for an abrasive element 70 mounted on said nut through said slot, an abrasive element mounted on said carrier, means whereby the assembled supporting member, screw, nut and carrier is oscillated about the screw shaft bringing the carrier into a position 75

where said abrasive element carried thereby is compressed against the face of a roll, means whereby said worm screw is given a reversing rotation, and a slip clutch between said means and said worm screw whereby movement of the means may continue after rotation of the screw is stopped by the arrival of said nut at the end of said slot.

5. In an automatic polisher for the upper roll of a two high mill equipped with an automatic lower roll polisher, including in combination, a hollow supporting member, a worm screw mounted therethrough, a worm screw nut mounted on said screw and non-rotatable in said supporting member, a polishing stone holder mounted on said worm screw nut, a polishing element mounted in said holder, means to oscillate said supporting member and said nut, with holder mounted thereon, to a position in which the element carried thereby is pressed against the roll, means driven by the lower roll polisher to impart revers-

ing rotation to said worm screw, whereby the said screw nut is moved forward and back across the face of said upper roll, and a slip clutch interposed between said means and said worm screw whereby movement of the former is possible when the latter is held immovable. 5

6. In combination in a device for polishing a roll of a mill, a worm screw shaft revolvably mounted, a worm screw nut mounted on said shaft and carrying a holder adapted to receive 10 a polishing element, means adapted to hold said nut against rotation with said shaft, means adapted to impart reversing rotation to said worm screw shaft synchronously with the reversing movement of mechanism polishing another 15 roll of the mill, and means independent of said last-mentioned means adapted to render same inoperative as to said shaft when said nut has reached a predetermined position thereon.

20

WILLIAM W. LEACH.
